[57] CLAIM

The ornamental design for an exercise flotation device, as shown and described.

DESCRIPTION

FIG. 1 is a perspective view of an exercise flotation device which illustrates my new design;

FIG. 2 is a top plan view thereof;

FIG. 3 is a front elevational view thereof, the rear elevational view being a mirror image thereof;

FIG. 4 is a bottom plan view thereof;

FIG. 5 is a left side elevational view thereof;

FIG. 6 is a right side elevational view thereof;

FIG. 7 is a perspective view of an exercise flotation device which illustrates an alternative embodiment of my new design;

FIG. 8 is a top plan view thereof, the bottom plan view being a mirror image thereof;

FIG. 9 is a front elevational view thereof, the rear elevational view being a mirror image thereof;

FIG. 10 is a left side elevational view thereof; and,

FIG. 11 is a right side elevational view thereof.
